WALK-IN STAIRWELL CLOSET

Kermit M. Pennington, 5811 Luce Road, and Robert D. Swanson, 313 Maple, both of Alma, Mich.

Filed Sept. 29, 1960, Ser. No. 59,379

5 Claims. (Cl. 20—5)

This invention relates to building construction, and particularly to building construction wherein a lowerable ramp means is provided for utilizing and gaining access to an otherwise inaccessible storage area located above a building stairwell.

In conventional residential building constructions, the various floors in the building are interconnected by stairways or steps, and an inclined ceiling is provided thereabove to finish off the area and eliminate the need for finishing off the vertical wall surfaces adjacent the actual ceiling, it being noted that by thus providing a false inclined ceiling the area to be finished off is substantially reduced.

The inclined false ceiling cooperates with the actual ceiling and the vertical walls around the stairwell to provide a dead space which is normally inaccessible and unusable. It has been proposed to gain access to this normally lost space by providing a doorway in the upper story, i.e. in one of the vertical walls making up the stairwell. However, such procedure necessarily subtracts from the usable wall space in the room from which the doorway is cut. In most instances the space above the inclined false ceiling is left inaccessible.

Under the present invention it is proposed to provide a novel arrangement for gaining access to the above mentioned lost space so that same may be used for storage purposes. Thus it is proposed to provide an opening in the false inclined ceiling above the stairway and to hingedly mount a drawbridge door or walk-on ramp within the formed opening so that when access to the otherwise lost space is desired, the door or ramp may be swung down toward the stairway steps and onto the landing or one of the uppermost steps. By this arrangement the householder is enabled to walk onto the ramp or drawbridge door and gain access to the otherwise lost space. The space may be equipped with any suitable form of storage devices, as for example clothes hanger hooks, closet poles, shelves, racks, drawers, etc.

One object of the present invention is to provide a construction of the immediately above discussed type which is of relatively low cost and which does not add appreciably to the cost of the building.

A further object of the invention is to provide a device of the above-mentioned type wherein operation thereof may be effected easily and quickly by persons having little or no mechanical aptitude, such, for example, as housewives.

A further object of the invention is to provide an apparatus of the above-mentioned type wherein the components thereof are suitably proportioned and designed to give adequate head room for the householder so that he is not required to stoop while entering the storage area.

A further object of the invention is to provide apparatus of the above-mentioned type wherein the walk-on ramp is provided with counter-balancing means so that housewives or other non-muscular persons may easily swing the ramp upwardly to the locked position.

An additional object of the invention is to provide an apparatus of the above-mentioned type wherein the ramp is substantially flush with the false ceiling in the locked raised position so that it blends with the surrounding wall area and does not detract from the general appearance of the home.

Other objects of this invention will appear in the follow-

2

ing description and appended claims, reference being had to the accompanying drawings forming a part of this specification wherein like reference characters designate corresponding parts in the several views.

5 FIG. 1 is a sectional view taken through one embodiment of the invention and illustrating the essential features thereof;

10 FIG. 2 is a sectional view taken in the same direction as FIG. 1 but showing a walk-on ramp thereof in a lowered position;

15 FIG. 3 is an enlarged sectional view taken substantially on line 3—3 on FIG. 1.

20 FIG. 4 is a fragmentary view showing the use of an electric motor with the FIG. 1 apparatus for powering purposes.

Before explaining the present invention in detail, it is to be understood that the invention is not limited in its application to the details of construction and arrangement of parts illustrated in the accompanying drawings, since 25 the invention is capable of other embodiments and of being practiced or carried out in various ways. Also, it is to be understood that the phraseology or terminology employed herein is for the purpose of description and not of limitation.

30 Referring to the drawings, and particularly FIG. 1, there is shown a building construction 10 including the conventional upright studs 12 and 14, the overhead joists 16 and the lower joists 18 and 20 which define the ceiling of the basement denoted generally by the numeral 22.

35 The upstairs area is denoted by numeral 30.

40 As shown in FIG. 1, access to the basement is provided by the conventional steps or stairs 24 supported on the conventional inclined stringers 26 extending downwardly from the studding 28. It will be understood that if desired the space between the two superjacent studs 14 (only one of which is visible in FIG. 1) may be equipped with a door to close off the first floor area 30, from basement 22.

45 The construction thus far described is conventional, and the invention is concerned therewith only to the extent that the components to be described hereinafter cooperate with the conventional structures in providing a novel access-storage arrangement. The arrangement includes a transverse lower header 32 and an upper transverse header 34, said headers being interconnected by two inclined parallel beams, one of which is shown at 36 in the drawings. These two beams are spaced from one another by a distance somewhat in excess of the width of an adult person, as for example thirty inches. By this arrangement the free space between the two beams 36 can be utilized to 50 gain access to the shelving 33 mounted on the closet wall 40. The upper and lower panels 58 and 33, along with the panelled areas outside of the beams 36, define a central free space or access opening.

55 As shown in FIG. 1 the central space between the two beams 36 is normally occupied by a walk-on ramp or drawbridge door indicated generally by the numeral 42.

Ramp 42 may be constructed in any of several ways, but as shown in the illustrative drawings the ramp comprises a plywood panel 44 secured to the undersurface of two 60 similar parallel longitudinal framing reinforcement members 46, only one of which is visible in the drawings. Members 46 extend substantially the entire length of the ramp so as to longitudinally reinforce the panels 44. Various transverse frame elements could also be provided to 65 provide strength in the transverse direction.

70 The walk-on ramp is hingedly mounted on the header 32 and short ceiling panel 33, as by means of the conventional hinge means 48. By this arrangement the walk-on ramp may be swung downwardly from its FIG. 1 closed position to the FIG. 2 open position. In the FIG. 2 position the free edge portion 50 of the ramp rests on the landing or upstairs flooring 52 so that a person may walk

from the flooring directly onto the ramp 42 to gain access to shelves 38. It will be understood that additional storage devices such as hocks, racks, drawers, etc. can be provided within the closet space.

The closet is of course of full adult walking height, so that the householder does not have to stoop while he or she is within the closet area. However, in order to provide an access to the closet area without requiring the householder to stoop as he or she enters the area, there may be provided a panel 54 hingedly mounted at 56 on one of the fixed ceiling panels 58. As shown in the drawings, panel 54 is provided with a cleat 60 so that the panels 44 and 54 may be accurately aligned flush with one another in the FIG. 1 closed position.

Cleat 60 is connected with a flexible element 62 which may comprise one or more chains, ropes, cables, etc. The flexible element is trained over suitable pulleys or guide elements 64 and 66 suitably mounted on the closet ceiling 68. The flexible element extends downwardly from engagement with guide element 66 to a fixed connection at 70 with the walk-on ramp 42. It will be noted that connection 61 is spaced approximately the same distance from the axis of hinge 56 as the spacing between connection point 70 and the axis of hinge 48. By this arrangement element 62 can at all times be maintained in a taut condition since as the ramp is moved downwardly the left portion of the flexible element is elevated substantially the same amount as the right portion thereof is lowered.

It will be understood that the provision of panel 54 and the cable-pulley means is optional and that the ramp 42 could be utilized in the absence thereof. Thus, the ramp could be elongated to have a length equivalent to the combined length of the illustrated ramp and panel 54 so as to provide desired head room. One advantage in utilizing an auxiliary panel 54 is that the ramp can be made somewhat shorter than otherwise would be possible, the shorter ramp being somewhat easier for the average person to move upwardly and downwardly.

Any suitable handle structure may be provided for pulling the ramp 42 downwardly. The drawings illustrate the handle means merely as a slot or opening 71 in the latch elements 86. The arrangement is such that the user merely extends his fingers through the slot and pulls downwardly thereon to lower the ramp. After the ramp has moved a short distance away from the fixed ceiling structure 58 the ramp may be moved to its final FIG. 2 position by manually grasping the edge portion 50 of panel 44.

Preferably a counterbalance mechanism is provided to cushion the weight of ramp 42 so that the householder is not required to support and hold the entire ramp weight as the ramp is being lowered. In the drawings there is shown a suitable counter-balance means which consists simply of a set of counter-balancing spring assemblies 72 such as are commonly used for the conventional heavy double hung windows. Each counter-balancing mechanism may comprise a fixed casing 74 suitably secured on one of the beams 36. A wind-up clockwork type leaf spring 76 is disposed within casing 74 and is extended therefrom to a connection with the adjacent frame 46, as at 80.

FIG. 3 illustrates the leaf spring 76 wound substantially completely into the casing 74; as the ramp 42 is pulled downwardly the spring is unwound from within the casing so as to exert its counter-balancing force. Preferably, the spring does not completely counter-balance the weight of the ramp so as to eliminate the necessity for a latching means which would otherwise be necessary to hold the ramp 42 in its FIG. 2 lowered position.

In order to latch the ramp in the raised FIG. 1 position there may be provided a pair of spring-urged latch mechanisms such as is shown at 82 in FIG. 3. As there shown the latch mechanism comprises a keeper member 84 suitably secured on a fixed ceiling panel 59, and a movable latching member 86 slidably positioned within a guide

member 88 suitably secured to the underside of the ramp panel 44.

The sliding latch element may be provided with an abutment washer, ring or the like 90 so that when the latch element is manually retracted in the arrow 92 direction, it is withdrawn from the keeper 84. A suitable compression spring means may be provided at 94 to automatically advance the latch element 86 to its illustrated position when the manual pressure is removed therefrom.

As shown in FIG. 3 the latch element may be provided with a cam surface 96, whereby when the user moves the ramp 42 upwardly from the FIG. 2 position the cam surface is caused to strike against an external edge of the keeper 84 so as to momentarily retract the latch and then allow the spring 94 to automatically advance the latch into the FIG. 3 locked position.

The locking of the ramp in the FIG. 1 raised position is therefore automatic without need for manual operation of the latch element. Preferably a latch mechanism 82 is provided adjacent each lateral edge of the ramp. The drawings illustrate but one type of automatic latching mechanism, and it is contemplated that other types of latch devices can be employed. Several types of such latches are available on the open market.

One feature of the invention which is worthy of note resides in the fact that as shown in FIG. 1 the undersurface of panel 44 is flush with the undersurface of panel 54 and fixed ceiling panel 58. By this arrangement the ramp blends in with the surrounding paneling so as not to detract from the appearance thereof.

A further feature of the illustrated arrangement is the fact that it is adapted to be powered with a conventional electric motor in the event that push button operation is desired. Thus, as shown in FIG. 4 a reversible electric motor 100 may be mounted on the underside of ceiling 68 with shaft 102 thereof having the cable 62 trained therearound as shown. By this arrangement energization of the motor in one direction pulls the cable to the right so as to lower the ramp, and energization of the motor in the other direction pulls the cable to the left so as to raise the ramp. A suitable starter button-switch and limit switches (not shown) may be provided to control the operation of the motor.

The drawings illustrate particular structures useful in practice of the invention, but it will be understood that variations may be resorted to without departing from the spirit of the invention as set forth in the appended claims.

We claim:

1. In a building construction including upper and lower levels with a floor on each of the levels, a ceiling structure over the upper level, an opening in the floor of the upper level, a stairway connected at its top end to the floor of the upper level at one end of the opening, the stairway extending down through the opening to the floor of the lower level, a short vertical wall extending down from the ceiling structure directly above the top end of the stairway, the short vertical wall terminating at its lower end a substantial distance above the top end of the stairway, a long vertical wall extending between the ceiling structure and the floor of the upper level directly above the bottom end of the stairway, an inclined panel secured to the lower ends of the vertical walls and being generally parallel to the stairway and positioned directly above the stairway, vertical sidewalls above the sides of the stairway and extending downwardly from the ceiling structure at least to the inclined panel, the vertical walls, inclined panel and that portion of the ceiling structure within the vertical walls defining an enclosed space, the improvement of, a rectangular opening in the inclined panel with the

lower ends of the inclined edges of said rectangular opening terminating at the lower end of the long vertical wall,
 said inclined edges being substantially as long as the horizontal distance between the short and long vertical walls,
 a ramp in said opening,
 said ramp having the lower end hinged to the lower end of the long vertical wall,
 releasable latch means holding said ramp in said opening,
 and said ramp being adapted to pivot from a position within said opening to a horizontal position wherein the upper end of said ramp engages the top end of the stairway and provides walk-in access from the floor of the upper level to the enclosed space.

2. The invention defined in claim 1 wherein said ramp is shorter than said opening,
 a panel in the upper part of said opening,
 said panel and said ramp totaling the length of said opening,
 said panel being hinged at its upper edge to the bottom of the short vertical wall to pivot upwardly into the enclosed space,
 a flexible line having one end connected to a lower part of said ramp and the other end connected to the lower part of said panel,
 and means within the enclosed space movably supporting the median portion of said line.

3. The invention defined in claim 1 and further including
 a counterbalance attached to a median portion of the inclined panel and to a median portion of said ramp, said counterbalance being of slightly lesser strength than the weight of said ramp,
 and cooperable latch means connected to the inclined panel and said ramp to retain said ramp within said rectangular opening.

4. The invention defined in claim 1 and wherein said ramp is shorter than said opening.

35

40

a panel in the upper part of said opening,
 said panel and ramp totaling the length of said opening,
 said panel being hinged at its upper edge to the bottom of the shorter vertical wall to pivot upwardly into the enclosed space,
 a flexible line having one end connected to a lower portion of said ramp and the other end connected to the lower portion of said panel,
 means within the enclosed space movably supporting a median portion of said line,
 a counterbalance attached to a median portion of inclined panel and a median portion of said ramp, and cooperable latch means connected to said ramp and to the inclined panel.

5. The invention defined in claim 1 wherein said ramp is shorter than said opening,
 a panel in the upper part of said opening,
 said panel and ramp totaling the length of said opening, said panel being hinged at its upper edge to the bottom of the shorter vertical wall to pivot upwardly into the enclosed space,
 a flexible line having one end connected to a lower portion of said ramp and the other end connected to the lower portion of said panel,
 means within the enclosed space movably supporting a median portion of said line,
 a motor mounted in the enclosed space adjacent said support means,
 said motor having a drive shaft,
 and a median portion of said line being drivingly trained around said shaft.
